(57) **CLAIM**

The ornamental design for a shelf as shown and described.

DESCRIPTION

FIG. 1 is an upper perspective view of a shelf showing my new design.

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines illustrate portions of the shelf that form no part of the claimed design.

1 Claim, 3 Drawing Sheets
